UNITED STATES PATENT OFFICE.

JAMES G. MASUMIAN, OF BROOKLYN, NEW YORK.

WINDOW-FRAME CONSTRUCTION.

1,284,123.

Specification of Letters Patent. Patented Nov. 5, 1918.

Application filed September 11, 1917. Serial No. 190,842.

To all whom it may concern:

Be it known that I, JAMES G. MASUMIAN, a citizen of the United States, residing at Brooklyn, in the county of Kings and State 5 of New York, have invented new and useful Improvements in Window-Frame Constructions, of which the following is a specification.

This invention relates to window frame 10 constructions and has for its principal object, the provision of a window frame so constructed as to house the shade rollers within the frame, thus concealing them from view and at the same time eliminating unsightly 15 nail or screw holes which are ordinarily left exposed when tenants remove the same from the ordinary frame work of the window.

Another object of the invention is the provision of a hinged panel which allows ready 20 access to the shade rollers for their removal or for the adjustment of the spring tension in the same.

A further object of the invention is the provision of a pair of grooves arranged 25 within the side panels of the window frame for the reception of curtain stays whereby the shade is prevented from bulging.

A still further object of the invention is the provision of a window construction of 30 the class described which is of simple construction, inexpensive to install and which overcomes many of the objections to the ones now in common use.

With these and other objects in view, the 35 invention resides in the novel construction, combination and arrangement of parts fully described in the specification, particularly pointed out in the appended claim and illustrated in the accompanying drawing, in 40 which,

Figure 1 is a fragmentary sectional view of the upper portion of a window.

Fig. 2 is a detail sectional view of one of the shades.

Fig. 3 is a fragmentary sectional view on the line 3—3 of Fig. 1.

Fig. 4 is a detail front elevation of the shade rollers.

Fig. 5 is a sectional view on the line 5—5 50 of Fig. 4.

Referring to the drawings by numerals, 10, designates generally a window frame of ordinary construction which has extending upwardly therefrom at its forward portion,

a shade roller housing 11. The shade roller 55 housing is provided with a swinging base section 12, which is normally disposed in the same horizontal line with the top panel 13, of the window frame. The swinging base 60 12, is slightly spaced from the forward portion of the top panel 13, to provide an intervening shade guide 14, therebetween, the said swinging base and panel co-acting to limit the projection of the lower portion of the shade within the housing. A pair of 65 shade rollers 15, are mounted in the brackets 16, which are secured within the housing and the shades 17, mounted on said rollers are provided with transversely arranged ribs 18, the outer extremities of which are adapted 70 to work within the grooves 19, with which the side panels 20, are provided. The lower portions of the shades are provided with transversely extending hollow members 21, within which are mounted the locking rods 22, which are normally impinged against the inner faces of the grooves by means of the springs 23. A pair of manipulating handles 24, are provided on the rods 22, whereby the latter may be relieved from the spring pressure when it is desired to raise or lower the curtain. The swinging base 12, is adapted to be moved to the dotted line position shown in Fig. 1, when it is desired to gain access to the shade rollers to remove the same or adjust the tension of the springs.

While I have shown and described a simple and preferred form of my invention, I desire to reserve the right to make such changes and alterations as fall within the scope of the appended claim.

What is claimed as new is:—

In a window frame construction of the class described, a main frame having several guides, side bars constituting a part of said frame and extending forwardly beyond said guides, a top bar also constituting a part of said frame, and a shade roller housing rising from said side and top bars respectively and including a swinging base section disposed in the same horizontal line with said top bar and spaced therefrom to constitute an intervening shade guide therebetween, the said swinging base also serving to conceal the shade rollers.

In testimony whereof I affix my signature.

JAMES G. MASUMIAN.
